UNITED STATES PATENT OFFICE.

CHARLES WALLACE HUNT, OF WEST NEW BRIGHTON, NEW YORK.

DESIGN FOR A GEAR-CASING.

SPECIFICATION forming part of Design No. 35,836, dated April 1, 1902.

Application filed February 14, 1902. Serial No. 92,126. Term of patent 14 years.

To all whom it may concern:

Be it known that I, CHARLES WALLACE HUNT, a citizen of the United States, residing in West New Brighton, in the borough of Richmond, in the city and State of New York, have invented and produced a certain new and original Design for Gear-Casings, of which the following is a specification, reference being had to the accompanying drawings, forming a part hereof.

This invention relates to casings for gearing, particularly such as the reducing-gearing used between stationary electric motors and the parts driven thereby, such as hoisting-drums; and it consists in the novel shape or form thereof as herein set forth.

In the drawings, Figure 1 is a view in side elevation of a casing which embodies the design. Fig. 2 is an edge view thereof.

The essential feature of the design is the body part, circular in outline as seen from the side and flattened elliptical in outline as seen from the edge, with a median line or

band of demarcation about its major circumference.

The body part above referred to (marked *a* in the drawings) is circular in outline, of substantial thickness as compared with its diameter, its shoulders *b* on opposite sides being well rounded off, so that its outline as seen from the edge is a flattened ellipse. About the major circumference of the body, midway between its sides, is a line or band *c* of demarcation. At its under part and on each side of the median line of demarcation the body flows by easy lines into a spreading base *d*.

I claim as my invention—

The design for a gear-casing, substantially as shown and described.

This specification signed and witnessed this 8th day of February, A. D. 1902.

CHARLES WALLACE HUNT.

In presence of—

ANTHONY N. JESBERA,
LUCIUS E. VARNEY.
